UNITED STATES PATENT OFFICE.

MICHAEL L. HILLER, OF NEW YORK, N. Y.

DESIGN FOR A SLIPPER-UPPER.

SPECIFICATION forming part of Design No. 14,605, dated February 5, 1884.

Application filed December 26, 1883. Term of patent 7 years.

To all whom it may concern:

Be it known that I, MICHAEL L. HILLER, of the city, county, and State of New York, have invented and produced a new and original 5 Design for Slipper-Uppers, of which the following is a full, clear, and exact description, reference being had to the accompanying drawings, making part of this specification, in which—

10 Figures 1 and 2 represent front views of slipper-uppers according to my design.

Similar letters of reference indicate corresponding parts.

This design relates to slipper vamps or uppers; and it consists of a slipper-upper ornamented with three star-shaped figures having arms with branching terminals, the adjoining arms of the three stars being united at their ends.

15 20 A represents a slipper upper or vamp, and B an ornamental figure embodied thereon. The ornamental figure B is composed of three star-shaped figures, C, the centers of which are

equidistant from each other. Each figure C is composed of radial arms, said arms having 25 terminal branches or twigs. The adjoining arms of the three star-shaped figures are united at their ends in such a manner that one ornamental figure is formed thereby. The upper may be perforated between the arms of 30 the star-shaped figures, as shown in Fig. 2.

Having thus described my design, I claim as new and desire to secure by Letters Patent—

The design for a slipper-upper, composed of three star-shaped figures formed of radial 35 arms having terminal branches, the adjoining arms of the figures being united at their ends, substantially as shown and described.

In testimony that I claim the foregoing as my invention I have signed it this 12th day of 40 December, 1883.

MICHAEL L. HILLER.
